UNITED STATES PATENT OFFICE.

EDWARD H. AMET, OF WAUKEGAN, ILLINOIS, ASSIGNOR TO AMET ENGINE COMPANY, OF WAUKEGAN, ILLINOIS, A CORPORATION OF ILLINOIS.

ENGINE.

SPECIFICATION forming part of Letters Patent No. 727,562, dated May 12, 1903.

Application filed June 11, 1902. Serial No. 111,097. (No model.)

To all whom it may concern:

Be it known that I, EDWARD H. AMET, a citizen of the United States, residing in Waukegan, in the county of Lake and State of Illinois, have invented a new and useful Improvement in Engines, of which the following is a specification.

My invention relates to improvements in engines, and more particularly to improvements in caloric or hot-air engines or engines having a cylinder, a heater at one end of the cylinder, a working piston in the cooler end of the cylinder, and a transfer-piston in the hot end of the cylinder. Heretofore in engines of this class the transfer-piston has been mechanically connected to and driven from the crank-shaft or other moving part operated by the working piston, and such engines have heretofore been somewhat complicated and expensive in construction and of limited efficiency in operation in respect to energy and power produced from the fuel consumed.

The object of my invention is to simplify the construction and materially lessen the cost of the engine, while at the same time greatly increasing its efficiency. I have discovered that by combining with the cylinder, its heater at one end thereof, and the working piston a free or independent transfer-piston (one having no mechanical connection whatever with the working piston, its crank-shaft, or any part connected to or driven from it) the efficiency of the engine, the power or energy produced by it from the fuel consumed, is wonderfully increased, while at the same time, of course, the engine is greatly simplified in construction and its cost of manufacture materially diminished. The free, independent, or disconnected transfer-piston

is balanced, or rather overbalanced, to cause it to return to the upper limit of its stroke when the engine is at rest by a spring or its equivalent, and when the fly-wheel is turned or the engine started in either direction the transfer-piston automatically moves in proper unison or time with the working piston, and it automatically adjusts or adapts its movement also to the load upon the engine or work being done by it as the same may be from time to time varied, so that, surprising as it may seem, the engine is absolutely self-gov-

erning. By increasing or diminishing the tension of the spring the stroke of the transfer-piston may be made shorter or longer and the speed of the engine increased or diminished. The engine is also preferably provided with a water-supply tank and a pipe leading therefrom to the cylinder at a point intermediate of the stroke of the working piston, so that water or other fluid may be fed into the cylinder. This also materially increases the efficiency or power of the engine.

My invention also consists in the novel construction of parts and devices and in the novel combinations of parts and devices herein shown or described.

In the accompanying drawings, forming a part of this specification, Figure 1 is a central vertical section of an engine embodying my invention. Fig. 2 is a plan view looking from the line 2-2 of Fig. 1.

In the drawings, A represents the frame. B is the cylinder. C is a heater at the upper end thereof, the same being of any suitable construction and using any suitable kind of fuel—liquid, gaseous, or solid. As illustrated in the drawings, the heater has a grate C' and is designed for burning coal, charcoal, or other solid fuel.

D is the power or working piston reciprocating in the lower or cooler end of the cylinder, and F is a free or independent transfer-piston reciprocating in the upper or hot end of the cylinder. The power-piston D fits closely in the cylinder, being furnished with the customary packing-rings d.

G is the main crank or power shaft, driven from the working piston D through the connecting-pitman d', the same being furnished with a fly-wheel G'.

The free or independent transfer-piston F is overbalanced or caused to normally return to the upper limit of its stroke by a counterbalance F', the same being preferably a spring rather than a weight, as a spring-counterbalance will operate to return the transfer-piston much quicker. The spring F' may be connected to the free transfer-piston in any suitable way, directly or indirectly; but it is most conveniently done by providing the transfer-piston with a stem f, which extends through the working piston and is provided

with an antifriction-roller f' at its lower end, which rests on a grooved horizontal arm f^2 of a bent lever F^2 , to the other arm of which the spring F' is connected. To adjust the tension 5 of the spring, its outer end, instead of being connected directly to the frame, is attached to an adjusting-lever F^3 , which is furnished with an adjusting-screw F^4 .

H is a water-supply tank having a small 10 water-feed pipe h leading into the cylinder B at a point intermediate of the stroke of the working piston D . The guide-groove of arm f^2 in the bent lever F^2 keeps the roller of the piston - stem f in place on the lever. The 15 heater C has an ash-box C^2 below the grate and a flue C^3 . To give a neater finish, the lower portion of the cylinder B may be enclosed in a case M .

K is a cock closing a pipe or orifice K' , leading 20 into the cylinder B , by turning or opening which cock the engine may be stopped. The water-feed pipe h has a small opening h' at its lower end for the admission of water from the tank H and a small opening h^2 above 25 the same for admission of oil or lubricant, which may also be placed in the tank H and by which the working piston D is automatically lubricated.

In operation the engine works without visible 30 exhaust and without noise. Whatever water or liquid may be sucked or drawn into the cylinder B on the upstroke of the transfer-piston through the feed-pipe h is converted into steam and forced to the hot end of the 35 cylinder on the downstroke of the transfer-piston, thus increasing the expansive action and the effective power-stroke of the working piston. Other fluids than air or water may be used as the expansive fluid.

40 To start the engine, the upper end of the cylinder being heated, all that is required is to give the fly-wheel or crank-shaft a partial turn and the engine at once begins to operate, the free transfer-piston automatically going 45 into phase or properly timing its movement with that of the power-piston. The transfer-piston fits loosely in the cylinder B , leaving a thin annular space around the same for the passage of the expansive fluid from the cold 50 to the hot end of the cylinder and from the hot to the cold end of the cylinder. Whatever fluid in liquid or other form is drawn into the cylinder B through the pipe h is returned to the tank H , after being again condensed, through said pipe, and the pipe is 55 furnished with no valve whatever, and there is no valve to the cylinder, the engine being entirely valveless.

A loop or strap f^4 , embracing the horizontal 60 arm f^2 of the bent lever F^2 , keeps the roller f' on the piston-stem f in contact with the lever F^2 .

The reason or theory of the successful operation 65 of my engine, wherein the transfer-piston is free and independent of the working piston and has no mechanical connection therewith, may be explained as follows: When

in starting the engine the fly-wheel is given a turn or partial turn by hand and the working piston is thus, for example, caused to 70 make its initial downstroke, the transfer-piston, which at this time is held counterbalanced by the spring at or near the upper or hot end of the cylinder, is likewise caused to begin moving downwardly by the suction or 75 reduction of pressure on its lower end produced by the downward movement of the working piston, which movement of the transfer-piston is continued and accelerated by the colder air flowing to the upper or hot end of 80 the cylinder and there becoming heated and expanding, the expansion of the air in the hot end of the cylinder and of further air flowing to the hot end of the cylinder as the transfer-piston continues its downward movement forcing the working piston to the lower limit of its stroke. The counterbalance or 85 spring then tends to return the transfer-piston to the upper end of the cylinder, and the momentum acquired by the working piston 90 and fly-wheel carries back the working piston, and the stroke of both pistons is repeated again and again continuously. As the transfer-piston is entirely free and independent of the working piston and has no direct or mechanical connection therewith, it is free to accommodate or time its stroke properly and automatically with that of the working piston or go automatically into phase therewith, and it consequently exerts no retarding or checking effect upon the engines, and it is to this, 95 in part, that I ascribe the increased power and efficiency of my engine over other hot-air engines heretofore in use.

I claim—

1. In an engine, the combination with a cylinder, of a heater at one end of the cylinder, a working piston and a free or independent transfer-piston, substantially as specified.

2. In an engine, the combination with a cylinder, of a heater at one end of the cylinder, a working piston, a free or independent transfer-piston, and a counterbalance to cause the transfer-piston to normally return to the heated end of the cylinder, substantially as 115 specified.

3. In an engine, the combination with a cylinder, of a heater at one end of the cylinder, a working piston, a free or independent transfer-piston, and a spring connected to the transfer-cylinder and causing it to return to the heated end of the cylinder, substantially as 120 specified.

4. In an engine, the combination with a cylinder, of a heater at one end of the cylinder, a working piston, a free or independent transfer-piston, a tank and a fluid-feed pipe leading to the cylinder intermediate of the stroke of the working piston, substantially as 125 specified.

5. In an engine, the combination with a cylinder, of a heater at one end of the cylinder, a working piston, a free or independent transfer-piston, a tank and a fluid-feed pipe 130

leading to the cylinder intermediate of the stroke of the working piston, said feed-pipe having in said tank a water-inlet and an oil-inlet above the water-inlet, substantially as 5 specified.

6. In an engine, the combination with a cylinder, of a heater at one end of the cylinder, a working piston, a free or independent transfer-piston, and a counterbalance to 10 cause the transfer-piston to normally return to the heated end of the cylinder, the cylinder having a cock for stopping the engine, substantially as specified.

7. In an engine, the combination with a cylinder heated at one end, of a working piston and a free or independent transfer-piston having no mechanical connection with the moving parts operated by said working piston, substantially as specified. 15

20 8. In a hot-air engine, the combination with a cylinder, of a working piston, and a free, spring-actuated, transfer-piston, substantially as specified.

9. In a hot-air engine, the combination 25 with a cylinder of an overbalanced free, or independent transfer-piston automatically maintaining its position in the hot end of said cylinder when the engine is at rest and when the engine is started automatically timing its 30 movement with the working piston, substantially as specified.

10. In a hot-air engine, the combination 35 with a cylinder heated at one end, of a working piston and a free or independent transfer-piston operating to automatically return to the hot end of the cylinder when the engine is at rest and to move in unison or in proper time with the working piston when the engine is started, substantially as specified. 40

11. In a hot-air engine, the combination with a cylinder heated at one end, of a work-

ing piston and a free or independent transfer-piston operating to automatically return to the hot end of the cylinder when the engine is at rest and to move in unison or in proper time with the working piston when the engine is started, and a water-inlet to 45 said cylinder, substantially as specified.

12. In a hot-air engine, the combination 50 with a cylinder heated at one end, of a working piston and a free or independent transfer-piston operating to automatically return to the hot end of the cylinder when the engine is at rest and to move in unison or in 55 proper time with the working piston when the engine is started, and a cock for stopping the engine, substantially as specified.

13. In a hot-air engine, the combination 60 with a cylinder heated at one end, of a working piston and a free or independent transfer-piston operating to automatically return to the hot end of the cylinder when the engine is at rest and to move in unison or in proper time with the working piston when 65 the engine is started, a liquid-supply tank, a feed-pipe leading therefrom to the cylinder, substantially as specified.

14. In a hot-air engine, the combination 70 with a cylinder heated at one end, of a working piston and a free or independent transfer-piston operating to automatically return to the hot end of the cylinder when the engine is at rest and to move in unison or in proper time with the working piston when 75 the engine is started, a liquid-supply tank, a feed-pipe leading therefrom to the cylinder, said feed-pipe having an inlet for oil or lubricant, substantially as specified.
